(57) **CLAIM**

The ornamental design for sink basin, as shown and described.

DESCRIPTION

FIG. 1 is a perspective view of a sink basin showing my new design;

FIG. 2 is a top view thereof;

FIG. 3 is a bottom view thereof;

FIG. 4 is a rear elevational view thereof;

FIG. 5 is a front elevational view thereof;

FIG. 6 is a left side elevational view thereof; and,

FIG. 7 is a right side elevational view thereof.

The broken lines showing of plumbing openings and the bottom side are for illustrative purposes only and forms no part of the claimed design.
